UNITED STATES PATENT OFFICE.

ROBERT BREYER, OF MILWAUKEE, WISCONSIN, ASSIGNOR TO PHOENIX HOSIERY COMPANY, OF MILWAUKEE, WISCONSIN, A CORPORATION OF WISCONSIN.

STOP MOTION FOR KNITTING MACHINES.

Application filed September 2, 1926. Serial No. 133,295.

The invention relates to a stop motion device of general application wherever it is desired to intercept the functioning of a machine of any kind whatsoever in accordance with some desired or preset sequence in the order of suspending the action of the controlled machine.

In the device herein selected for specific disclosure there is featured a stop motion device 10 signed for installation in connection with a straight bar knitting machine, for instance a knitting machine of the type used in forming the flat blank of a full fashioned ladies' stocking, and which machine is otherwise provided with its conventional form of manually actuated stopping and starting mechanism.

In the knitting of a full fashioned stocking it is necessary for the machine to be stopped six or seven times during the course 20 of the knitting to permit the operator to perform the operation of "turning welts". For instance, the machine must be stopped to change from one kind or size of yarn to another as from cotton to silk, it must be stopped 25 to make the proper motions which put the machine in condition for knitting the welt, the leg, the high heel, the heel, the loose courses, the ravelling courses and the like.

Not only is it necessary to stop the machine 30 at these different points but with different types and sizes of stockings the points in the progress of the knitting at which the several stops must be made differ with each character of stocking being knit.

Attempts have been made heretofore to 35 provide the machine with stop mechanism intended to be set to stop the machine automatically at the prefixed points in the knitting operation of the different types and sizes of stockings in order among other things to 40 attain uniformity in the knitting of the several parts of stockings of the same type or size. Such known stopping devices however have not proven satisfactory in practice especially in a large plant where numerous machines are in operation knitting the same 45 character of stocking, for each separate machine must be set independent of the setting of the other machines with resulting loss of 50 labor and time for the machines must remain idle during the period necessary to effect the resetting of the stop motion controlling the same. Further, this separate resetting of the controls for each machine permits the introduction of a factor of error which results in 55

the stockings knit by one machine differing from those knit by another machine unless unusual, painstaking and practically impossible precautions are taken by the operator to set the controls for all the machines exactly 60 alike.

Another objection to knitting machine stops heretofore known and where the setting of the machine involves an adjustment of mechanical parts, is that in operation the adjustable stops are apt to be jarred or worn from any mathematically exact position in which they may be initially set with resulting inaccuracies of the subsequent operation even if the setting was initially correct. Mechanically adjustable control devices of the known types are not designed for micrometrical adjustments and therefore do not lend themselves readily to being set to stop the machine at any definite numbered course in the knitting machine and at best machines controlled thereby can be set to stop only approximately at the desired point and not exactly at the desired point. Such structures are further objectionable in that they do not facilitate a 70 quick resetting of the machine to knit a different size or type of stocking and therefore limit the use of the controlled machine to the knitting of one size and type of stocking until 75 each of the controls have been individually reset to accommodate the machine to knit a different character of stocking.

Accordingly, the primary object of the invention is to provide a simplified form of stop motion which can be set with mathematical exactness to stop the machine controlled thereby exactly at preset places in its sequence of operative movements and which sequence of stopping operation will be independent of any wear in the control mechanism, to provide a control which can be set exactly so that sequence of stops in the machine controlled thereby can be duplicated exactly in the knitting operation of other machines and to provide a stop motion which 90 can be quickly changed from one to some other set of sequence of stops without necessity of making any mechanical adjustment in the structural parts of either the stop motion or the machine controlled thereby.

Broadly, this phase of the invention is attained by providing a stop motion device 100 preferably in the form of an attachment to the machine which it controls and which stop motion derives the power necessary to actu-

ate the same and is controlled in its timed action by the controlled machine, and by providing a replaceable card or perforated jacquard, one for each size or type of stocking or other article to be knit, operatively disposed in control of the power actuated stop mechanism to cause the same to function in a timed sequence depending upon the character of the pattern on the particular card for 10 the time being in control of the stop motion.

Another object of the invention is to provide a simple form of stop motion device for full fashioned stocking knitting machines which will defeat any attempt on the part of 15 the operator to vary the number of courses knit in the several parts of the stocking as preset for any particular type or size of stocking, and at the same time to provide a stop motion device which will not interfere with 20 the operator's control of the machine to effect a stopping thereof whenever desired but which extra stopping will have no effect upon the order of automatic stoppings for which the machine is set.

25 The invention herein disclosed features the use of a readily replaceable card or jacquard for controlling the stop motion and in this connection another object of the invention is to provide the replaceable card of a small size to facilitate the storing of a large number of cards and at the same time to provide for extreme refinement in controlling operations in situations where there is a large number of cycles of knitting or other operative 30 actions of the control machine at any one of 35 which the machine may be stopped.

In one aspect of the disclosure this is attained by forming the jacquard of a relatively short length of paper, fibrous or other 40 suitable composition which can be readily rolled into a compact space for storage and which may be perforated with apertures sufficiently large to accommodate the controlling needles coating therewith without weakening the card. There is thus featured a stop motion the controlling card of which is not easily mutilated while in use. Another object of the invention is to provide a jacquard controlled stop motion which can be duplicated 45 in its mechanical parts so that a multiplicity of machines may be controlled from facsimiles of a master jacquard, and thus insure uniformity of products where a large number of knitting machines are simultaneously producing the same size or type of 50 stocking.

55 Still another object of the invention is to provide a stop motion for full fashioned stocking knitting machines which can be set for any particular type or size of stocking; which will insure the knitting of all of the 60 courses preset for that particular character of stocking; which will be automatically swung out of operation when the complete number 65 of courses have been knit and which will tend

to defeat attempts to knit any less number of courses as long as a particular jacquard for such stockings is controlling the operation of the stop motion.

Various other objects and advantages of the 70 invention will be in part obvious from an inspection of the accompanying drawings and in part will be more fully set forth in the following particular description of one form of device embodying the invention, and the 75 invention also consists in certain new and novel features of construction and combination of parts hereinafter set forth and claimed.

80 In the accompanying drawings, Fig. 1 is a view in front elevation of an attachment for a straight bar knitting machine constituting a preferred embodiment of the invention and shown in operative relation to the coating elements of the controlled machine with the parts in normal inoperative position;

85 Fig. 2 is a view in side elevation of the device shown in Fig. 1 looking at the same from the right hand side of this figure and with parts omitted;

90 Fig. 3 is an enlarged view of some of the parts shown in Fig. 1 with the machine stopping member omitted and showing in dotted lines the disposition of the parts while this member is being shifted;

95 Fig. 4 is a horizontal sectional view taken on the broken lines 4—4 of Fig. 1 looking downwardly as indicated by the arrows and with the jacquard and power cams of the controlled machine omitted;

100 Fig. 5 is a vertical sectional view taken on the line 5—5 of Fig. 4 and showing the parts on one side of the standard when looking in the direction indicated by the arrows;

105 Fig. 6 is an enlarged view mostly in elevation of the parts shown in Fig. 3 looking at the same from the left of said figure and with parts of the roller and its shifting carriage broken away;

110 Fig. 7 is an enlarged view in side elevation of the upper part of the jacquard and associated mechanism in the position of the needles while the jacquard is being fed in step with the controlled machine;

115 Fig. 8 is a view largely in elevation of the ratchet feed as the corresponding parts are viewed from the line 8—8 of Fig. 2 and looking in the direction indicated by the arrows and with the ratchet pawl shown in succeeding positions in full and dotted lines;

120 Fig. 9 is a view similar to Fig. 8 showing the ratchet feed in position to retract the units and ratchet;

125 Fig. 10 is a detail of the jacquard controlled stop for intercepting the ratchet feed taken on the line 10—10 of Fig. 2 looking in the direction indicated by the arrows;

130 Fig. 11 is a view corresponding to Fig. 10 showing the arrangement of the parts with

the ratchet feed locked in inoperative position in the final stop;

Fig. 12 is a detail view of the jacquard sprocket and coating needles shown in position when the machine is stopped prior to the final stop; and

Fig. 13 is a plan view of a controlling jacquard and laid out in a flat strip to show the jacquard pattern.

10 It is understood that the machine herein featured is designed to constitute an attachment to any of the several forms of straight bar knitting machines now in general use and that in this disclosure there has been illustrated only so much of such a machine as is necessary to show the installation of the attachment herein featured.

In the drawings there is shown a straight bar knitting machine of the type used for knitting full fashioned stockings and which machine includes a support 14 for the attachment and which support is any convenient or suitable part of the machine to be controlled, but it is obvious that the attachment may be provided with its own support independent of the machine. There is also illustrated in Fig. 1 a portion of a starting rod 15 which is connected conventionally to a control switch or other instrumentality for starting and stopping the knitting machine. There is also disclosed one of the power shafts 16 which move in synchronism with the knitting mechanism one revolution for each course knit all as is well known in structures of the type disclosed. The shaft is provided with a pair of cams 17 and 18 (Fig. 4) secured thereto and operatively connected to actuate the mechanism herein featured and for which reason the shaft will be referred to hereinafter as a cam shaft. The cams are designed to actuate the machine elements engaging the same once for each rotation of the shaft and the rise on the cam 17 is about ninety degrees in advance of the rise of the cam 18 which disposition was found necessary in the specific form of the invention illustrated. This disposition of an aperture aligned with each aperture *m* is necessary on the succeeding rotation of shaft 16 to remove aperture *m* promptly from its position in line with needle 85 in order to insure the proper timing of the mechanism governed thereby.

The attachment herein featured constitutes a complete article of manufacture and comprises a standard 19 in the form of a heavy thick steel plate. The bottom of the standard is defined by a foot 20 adapted to rest on the support 14 with one end defined by a depending toe 21 and the other end defined by a heel 22 secured to the foot 20 by bolts 23 and constituting a means for demountably clamping the attachment to the machine.

Pivoted to the front side of the standard on a pivot pin 24 (Fig. 1) is a long lever 25 herein referred to as a machine stop-

ping member. The upper end of this member is fitted between a pair of collars 26 and 27 secured to the starting rod 15 so that the swinging of the lever about its fulcrum support in a movement from right to left and from the full line into the dotted line showing in Fig. 1 will cause the machine to stop its knitting operation. It is understood that the starting rod may be otherwise actuated, for instance, as by manual operation of the operator and that a reverse movement of the rod, from left to right, will start the operation of the knitting machine through mechanism forming no part of the present disclosure.

Positioned on the lower arm of the machine stopping member 25 is an L-shaped member 28 hereinafter referred to as a reversible cam nose and which is secured to the member 25 by means of a pair of replaceable bolts 29 and 30. A laterally projecting end of the cam nose is provided on its upper side with a beveled face 31 adapted to be engaged by a roller 32 hereinafter more fully described. In place of the arrangement shown in Fig. 1 where the stopping movement of the rod 15 is from the position shown in full line to the right and into the position shown in dotted line, it is desirable under some conditions to reverse the direction of stopping movement. For instance, it may be necessary to effect a stopping of the machine by a right to left movement of the control rod, as from the dotted line into the full line position shown in Fig. 1. In this case it is suggested that the cam nose be reversed to the opposite side of the roller 32 and for this purpose there is provided a U-form of linkage for carrying the cam nose. This linkage includes an apertured arm pivoted on a bolt 34 positioned on the opposite side of the roller from the bolt 24. The lower end of the arm 33 is connected with the lower end of the member 25 by means of a connecting link 35. The arm 33 is provided with a pair of apertures 36 and 37 for receiving respectively the bolts 29 and 30 when the cam nose is mounted on this arm and with its beveled face 31 underlapping the roller 32.

The roller 32 is provided with a hub 38 (see Fig. 6) and is rotatably mounted upon a stud shaft 39 carried by a lever controlling slide bar 40 mounted for vertical reciprocatory movement in a guideway 41 formed in one side of the standard 19. The slide bar is normally maintained in its elevated position by means of a long spring 42 the upper end of which is secured to a projection 43 secured to the rear face of the standard by screws 44 and hereinafter referred to as a spring housing. The lower end of the spring 42 is secured to a projecting end of a pivot pin 45 mounted in a pair of ears 46 projecting rearwardly from the slide bar 40 through an elongated slot 46 formed in the standard. The slide bar is re-

ciprocated by the rotary action of the cam 17 (Fig. 4) to which it is connected by a cam lever 47 pivoted by means of bolt 48 to one side of a heavy bracket 49 projecting rearwardly from the standard. Rotatably mounted on the rear end of the arm 47 is a roller 50 having a peripheral bearing engagement with the periphery of the cam 17. The opposite or inner end of the lever 47 (Fig. 6) is connected by means of a depending link arm 51 the lower end of which is pivotally mounted between the ears 46 on the pin 45.

For the purpose of providing adjustment between the roller 50 and the cam 17 fixed on the cam shaft the end of the arm 49 carrying the roller is provided with an arcuate slot 52 in which is mounted a roller shaft 53 carrying the roller 50 and which shaft is secured in adjusted position in the slot by means of a nut 54 bearing on a washer 55 in turn engaging the side of the arm.

From this construction it is understood that the long spring 42 acts to maintain the roller 50 at all times in proper bearing engagement with the cam and that as the cam turns in synchronism with the operation of the knitting machine the slide bar 40 and with it the roller 32 carried thereby is reciprocated vertically and this reciprocatory movement is continuous as long as the crank shaft is turning or in other words as long as the knitting machine is functioning.

The roller 32 is normally maintained so as to reciprocate idly out of operative engagement with the cam nose 28 as shown in full lines in Fig. 6. For this purpose the hub 38 of the roller is provided with peripheral groove 56 engaged by the bifurcated forked end of a yoke arm 57 constituting part of a horizontally movable roller shifting carriage 58. The upper end of the yoke arm 57 is secured by means of a pair of spacing bolts 59 to a plate 60 slidably mounted on a pin 61 projecting forwardly from the standard. The plate 60 is secured to a plunger 62 passed through an aperture 63 in the standard and intruded into the open end of the spring housing 43. A spring 64 in the housing bears on its end of the plunger and tends normally to maintain the carriage as a whole and with it the roller 32 in the projected, full line position shown in Fig. 6. The carriage is shifted inwardly in the direction indicated by the arrows in Fig. 6 by means of a small roller 65 journalled in a bracket 66 secured to the forward side of the slide plate 40 and adapted to engage the beveled end 67 of a bell crank lever 68 journalled on screw 70 threaded into the plate 60. Stop pins 71 and 72 projecting from the plate 60 limit the rocking movement of the lever. The bell crank lever is in turn rocked to and from its position to bring the beveled end in the path of movement of the reciprocating roller by card controlled mechanism hereinafter described.

From the parts thus far disclosed it is apparent that the rocking of the bell crank lever 68 into the path of movement of the reciprocating power driven roller 65 will in turn shift the roller 32 from the full line into the dotted line position in Fig. 6 so that in its downward movement under the action of the cam controlled slide 40 the machine stopping member 25 will be shifted by the engagement of the roller 32 with the cam nose 28 and the knitting machine will be stopped automatically. When the bell crank lever 68 is restored to its normal position out of the path of movement of the reciprocating roller as shown in full lines in Fig. 6 the spring 64 will react to shift the roller 32 out of the plane containing the cam nose and the continued operation of the machine with the parts so disposed will be without effect on the stopping member 25.

It is a feature of this disclosure that the stopping of the machine is controlled by the pattern on a card or jacquard and which pattern is designed to cause an automatic stopping of the machine at preset timed intervals, the unit of time being the lapsed duration while the cam shaft 16 is making one complete cycle of its rotary movement. In the illustrated showing the jacquard *j* (Figs. 7 and 13) for the time being in control of the machine is an endless strip of paper provided along opposite edges with sprocket apertures *s* designed to engage edge sprocket teeth 73 in a step-by-step feed sprocket 74 loosely mounted on a stub shaft 75 projecting forwardly from the standard as particularly shown in Fig. 4. This sprocket is driven from the cam shaft by means hereinafter described.

The jacquard is also looped about three guide rollers (Fig. 1) positioned below the sprocket and acting to place the necessary tension on the paper jacquard and at the same time feature a ready and conveniently actuated means for insuring a quick replacement of the jacquard. The guide rollers include two rollers 76 and 77 the axis of which are either fixed or intended to be fixed in adjusted position. The roller 78 is mounted at the free end of arm 79 extending from the shaft 80 which carries the roller 77 and designed by virtue of the weight of the arm and roller 78 to provide the necessary tension of the jacquard so as to maintain it in snug engagement with the upper face of the sprocket during the actuation of the machine. It is apparent from the disclosure that there is featured an arrangement by means of which the jacquard on the machine may be readily removed and replaced by a similar jacquard provided with a different pattern simply by lifting the arm 79 and then lifting the jacquard free of the sprocket teeth 73. This is done when it is desired to change the sequence of intervals between the stopping of the machine as would be the case where a

different size or different type of stocking or other article is to be knit by the controlled machine. The shaft 81 carrying the roller 76 is slidably mounted in a slot 82 formed 5 in the standard and the shaft is adjustably secured in the slot by means of a nut 83.

The pattern in the jacquard for regulating the sequence of stopping actions of the device is defined by a series of needle engaging 10 apertures punched through the paper strip. In the specific form of jacquard illustrated in Fig. 13 the apertures are arranged in three lines hereinafter identified as the unit apertures *u*, multiple apertures *m* of which 15 there are seven sets of each and a final stop aperture *f*.

The pattern forming apertures in the jacquard are designed to have control needles pass in to the same as these apertures are 20 moved into registry with the needles and the needles are designed to be held in an elevated position by the imperforated part of the jacquard between the apertures. The needles of which three are shown in the illustration (Figs. 2, 3, 7 and 12) are mounted for 25 vertical reciprocatory movement in a guide bar 84 projecting laterally from the standard and in alignment with the axis of the sprocket and spaced a short distance above 30 the sprocket.

One of the needles 85 is adjustably secured in an extension foot 86 overlapping the guide bar and formed at the free end of a horizontally extending arm 87 pivoted to the 35 front of the standard on pin 88. The arm 87 is connected intermediate its length with a depending L-link 89, the lower end of which is pivotally connected by means of pin 90 to the tripping lever 68. The pin is in the plane 40 of movement of the multiple apertures and is positioned over the same as they are advanced with the advance of the jacquard as shown in 45 Figs. 7 and 12. From this construction it is appreciated that whenever one of the apertures *m* is brought below the needle 85, the 50 needle falls by virtue of its own weight and by virtue of the weight of the arm 87 and L-link 89 passes through the aperture. The 55 lower reduced end of the needle is permitted to pass into an annular slot 92 formed below the needle in the sprocket wheel as particularly shown in Fig. 12. The falling of the 60 needle through the aligned aperture *m* permits the shifting of the beveled end 67 of the 65 lever into the path of movement of the reciprocating roller as shown in dotted lines in Fig. 3 and the stopping member 25 is shifted by power derived from the controlled machine as hereinbefore described.

60 The needle 85 and with it any of the other needles hereinafter described which may have been lowered into their associated apertures are elevated out of its and their apertures on the next succeeding upward movement 65 of the slide bar 40. This is attained by

means of an E-shaped needle elevating frame 93 (Figs. 1 and 3) one bar 94 of which is slidably mounted in a guide way 95 formed in the front face of the standard. The other bar 96 is provided at its own lower end with a forwardly extending lifting bar 97 Fig. 12 positioned between the needle bar extension 86 and the guide bar 84 and so disposed that it works idly when the needles are elevated but engages the needle to lift the same from their 70 depressed position in the jacquard apertures whenever the needles are in their lowered position as noted, for instance, in Fig. 12. The elevating frame 93 is lifted by the sliding bar 40 by means of a lifting finger 98 forming an 75 extension from the bracket 66 secured to the slide bar. The finger 98 underlaps a depending pin 99 carried by an L-shaped lifting bracket 100 secured to the front side of the lower end of the bar 94. From this construction 80 it is seen that the elevating frame is lifted and any depressed needles are lifted clear of the jacquard with each upward movement of the slide bar 40. Differently expressed the needles are lifted clear of the jacquard with each rotation of the cam shaft 16. 85

The jacquard *j* is advanced with a step-by-step motion in timed sequence with the actuation of the controlled knitting machine, and for this purpose the sprocket 74 is advanced 90 by a ratchet feed in turn advanced periodically by the turning of the cam 18 and in step therewith. One end of the sprocket is provided with a relatively small diameter one way ratchet 101 and which ratchet is intended 100 in the normal operation of the device to have a relatively slow step-by-step movement compared to the time of rotation of the controlling cam 18 and for which reason this ratchet directly controlling the sprocket will 105 be referred to as a slow speed unit step ratchet. Loosely mounted upon the shaft 75 which carries the sprocket is a multiplier 102 provided with the same number of teeth as the ratchet 101 and which multiplier 102 110 is designed to be advanced one notch for each cycle of rotary movement of the controlling cam 18. The multiplier 102 is of slightly greater diameter than the ratchet 101 but one of the V-shaped clearances or troughs 115 between a pair of succeeding teeth as shown at 103 in Figs. 3 and 6 is of greater depth than the others and this deep trough 103 corresponds in dimension to the clearance between the teeth of the ratchet 101 and is designed to be disposed opposite to the troughs 120 between the teeth forming the multiplier 102 so that a feed pawl 104 in its normal feeding engagement with the ratchet will periodically be advanced into the deep trough 125 103 and at the same time into whichever of the troughs which happen to be opposite the same so that in the next succeeding advance of the pawl both ratchets will be advanced one step. From this construction it is seen 130

that the sprocket wheel is advanced one step for each complete rotation of the multiplier.

In the illustrated form of the invention there are twelve movements of the multiplier 102 and correspondingly twelve rotations of the controlling cam for each single advancing step of the sprocket 74 and of the jacquard carried thereby while the needle 85 is in its normal control of the stop motion.

10 The pawl 104 is of the gravity type and is pivoted on pin 105 projecting from a rocking arm 106 pivotally mounted on a bearing ring 108 secured to the front of the standard concentric of the shaft 75. The rocking arm is normally maintained in position resting on a vertically adjustable stop 109 by means of a long spring 110. The stop 109 is in the form of a roller carried on an arm 111 (see Fig. 4) lapping the adjacent edge of the standard and forming a lateral extension from a ratchet feed slide 112 mounted for vertical reciprocatory movement in a guide way 113 formed in the rear side of the standard. The slide is connected by means of an L-link 114 to a cam roller arm 115 pivoted at its forward end by means of a pin 116 to the bracket 49 and on the side thereof opposite the cam arm 47. The free end of the arm 115 is provided with a cam roller 116' maintained by its weight in engagement with the periphery of the power cam 18.

From this description it is seen that with each unit rotary movement of the cam shaft 16 the ratchet feeding pawl is advanced a distance to turn the multiplier 102 one step. As this pawl is connected to the constantly rotating cam shaft it would mean that the pawl is reciprocated relative to its associated ratchet continuously as long as the controlled machine is in operation and that in the instant case the jacquard is advanced one step with each twelve rotations of the cam shaft. It therefore follows that the machine will be stopped automatically at each twelfth revolution of the cam shaft, or in multiples of twelve depending upon the spacing of the apertures *m* along the length of the jacquard.

It is apparent that by designing the stop motion so that it will advance the jacquard after a multiple turn of the cam shaft rather than to have the jacquard advanced in step with the turning of the cam shaft, reduces the total length of the jacquard for in most cases the time delay between required stopping of the machine is defined by two or three hundred rotations of the cam shaft. To have the jacquard advance a step at a time with the rotation of the cam shaft would necessitate a jacquard too long for convenient storing of a large number of jacquards and would increase the possibility of damaging the same both while in use and while handling the same.

It is obvious however that there will be times in the knitting of an article where it

is desired to stop the machine at some point which does not happen to be an exact multiple of the number of teeth in the unit ratchet wheel. Suppose, for instance, that after the machine has been stopped at the point indicated at *a*, Fig. 13, it is desired to knit say ninety-two courses before the machine is again stopped. This means that the previously described sprocket feed could be used for eight-four (seven times twelve) turnings of the cam shaft and which would advance the sprocket seven steps by the mechanism previously outlined. This leaves eight more turns of the cam shaft before the machine is to be stopped. This addendum number of courses to be knit is attained by throwing out of action the multiple feed mechanism and substituting a single step ratchet feed which will advance the sprocket in step with the cam shaft until the requisite number of additional courses are knit after which the machine is stopped as previously described.

This shifting of the sprocket feed from a multiple to a single timed movement of the cam shaft is attained by suitably disposed apertures *u* in the jacquard coacting with another of the needles slidably mounted in the guide bar 84. This is attained by causing the pawl 104 to engage directly succeeding teeth of the multiplier 102 and to dispose the pawl in an idle position relative to the unit ratchet 101. The positions of the apertures *u* in the jacquard are so arranged that the step-by-step feeding of the jacquard feeding sprocket in synchronism with the unitary turn of the cam shaft is started when the pawl is in engagement with the deep trough 103 and accordingly when it is in engagement with the sprocket ratchet.

The needle 117 which controls the setting of the pawl advance is in the form of an inverted U, one leg 118 of which slides vertically in the guide bar 84 and the other leg 119 slides in a guiding bracket 120 projecting forwardly from the standard. The lower reduced end 121 of the leg 118 is designed to drop into the jacquard apertures *u* as they are advanced with the jacquard into opposition to the reciprocating needle 117. In the normal, multiple feeding operation of the device and as an imperforated part of the jacquard is advanced beneath the needle it is kept from falling past the jacquard and the sprocket feed operates as previously described.

The lowering of the pin end 121 into one of the apertures *u* permits a tripping head 122 carried by the leg 119 to be lowered from the position shown into the path of the upper arm 123 of a normally inactive retractile lever 124. This lever is pivoted intermediate its length on a pin 125 carried by a bracket 126 secured to one side of the rocking arm 106.

In the normal, multiple feed operation of the sprocket this retractile lever rests within the full line position shown in Fig. 8 and has no function except as a stop for engaging against the adjacent side of the guide bar 84 as shown in dot and dash lines in Fig. 8 to limit the operative upward or clockwise movement of the arm 103. At this time it will be noted that the tripping head 122 is 10 slightly above the arc of movement of the arm 123. When the tripping head is lowered as shown in Fig. 9 by the descent of the pin 121 into an aperture *u*, the underside of the head is engaged by the upper curved side 127 of the lever and the upward swing of the arm 103 will cause the lever 124 to swing with its advanced arm 123 depressed from the position shown in Fig. 8 into the position shown in Fig. 9.

20 The lever 124 is provided on one side with a laterally extending pin 128 which is designed to engage back of a coacting pin 129 projecting laterally from the multiplier 102 and so disposed that when the rocking arm 25 106 is lowered under action of the spring 110, the multiplier 102 is retracted one step. In other words, the deep trough 103 in the ratchet wheel retreats back with the pawl therein so that on the next succeeding advancing stroke of the pawl it will be in engagement with the next tooth of the sprocket ratchet 101. From this construction it will be understood that the sprocket will be advanced one step with each actuation of the 30 pawl and this action will continue as long as the needle 117 controlling the head 122 is permitted to fall into aperture *u* in the jacquard. In the illustrated instance the sprocket will be advanced eight times, one 35 for each of the apertures in the group *b*, before the needle 85 has been caused to drop into a properly located aperture *m*. In this way the machine is stopped at the termination of ninety-two rotations of the cam shaft. 40 Assuming that the cam shaft turns once for each knitting course it is seen that the machine is stopped automatically at the termination of the ninety-second knitting course. 45

It will be noted from Fig. 13 that there 50 is an aperture *u* aligned with each of the machine stopping apertures *m*. This will mean that when the machine is stopped the head 122 will be in the lowered position shown in Fig. 9 and on the first elevation of 55 the stop 109 deep trough 103 retreats back with the pawl as above described. This is obviously necessary in order to permit the first rotation of the cam shaft, after it has been previously stopped, to promptly advance the jacquard to remove the previously 60 acting apertures from beneath the reciprocating needles.

For the purpose of stopping the feeding of the ratchet mechanism at the end of the knit-

ting operation and for locking the same in its stopped position the jacquard is provided with a single stop aperture *f* designed to be engaged by the third of the set of needles illustrated. This needle 130 constitutes one leg of a U-member slidably mounted in the 65 guide bar 84, the other leg 131 of which is provided with a beveled end 132. When the needle drops into the stop aperture *f* the end 132 is caused to engage the head 133 of a pawl lever 134. This lever is fulcrumed on 70 pin 135 carried by an extension bracket 136 secured to and projecting laterally from the front end of the guide bar 84. The lever is provided with a cam face 137 which when elevated by the jacquard needle is curved 75 concentrically of the ratchet carrying shaft 75. This cam face underlaps the free end of a long rod 138 which extends across the width of the sprocket and has its opposite end secured to the side of the pawl 104. The 80 parts are designed so that the elevated cam face engages the rod and acts therethrough to lift the pawl from engagement with the teeth of its associated ratchet 102. Even if the arm 106 carrying the pawl continues to 85 rock it will have no effect on the ratchet feed and thus no effect on the jacquard for the pawl will be simply sweeping idly over the ratchets and this will continue until the machine is stopped by one of the apertures *m* 90 or otherwise as by manual control of the rod 15.

The pawl is locked in its raised, inoperative position by the engagement therewith of a hanging latch 140 pivoted on pin 141 to the 100 outside of brackets 136. The latch 140 is provided on its inner edge with a notch 142 disposed to receive a pin 143 projecting through an opening in the bracket from the cam lever 134. With the pawl thus held in 105 inoperative position, the jacquard may be turned idly, reset to again start the control of the knitting operation or another jacquard may replace the one on the machine for a 110 different size or style of stocking or other article to be knit.

In operation and assuming that it is desired to use the device herein featured for the purpose of controlling the requisite stops incidental to the knitting of a full fashioned stocking and for which particular stocking a jacquard has been prepared, the jacquard is inserted on the feed sprocket and threaded through the machine as is clearly shown in Fig. 1 and with the point *c* of the jacquard on top of the sprocket and in line with the needles.

It is of course understood that the apertures forming the stop pattern on the jacquard have been designed and disposed in their spaced apart relation so that when the knitting operation has once started the machine will be stopped at the end of a certain 125

number of courses in the knitting operation as is defined by the spacing of the apertures *m* and *u* in the jacquard.

Assuming that there are twelve courses knit for each unit advance of the jacquard as indicated by the spacing of the feed sprocket apertures *s*, it will be noted that the machine will continue to function until one hundred and eight courses have been knit at which time the two needles 85 and 117 will come into operative engagement respectively with the apertures *m* and *u* at the point indicated at *a* on Fig. 13. The machine will be automatically stopped as previously described. The operator will then turn the welt following conventional practices and by shifting the control lever will again start the operation of the machine. The first movement of the machine will cause the jacquard to be advanced one step and the needles will then be opposite the unperforated space marked *d*. The machine will then continue to operate, in the instant case, advancing the jacquard one step with the knitting of each twelve courses until the needle 117 drops into the first of the set of apertures *b* after which for eight succeeding courses the jacquard will be advanced one step until seventy-eight courses when the machine is again stopped by needles 85 and 117 dropping into apertures *m*, *u* at the point *c*. When the machine is again started the knitting will continue for two hundred and twenty-four courses as indicated by the seventeen sprocket apertures between points *e* and *g*. It is understood that the operation is continued as previously described, the machine stopping automatically as the needles fall into the succeeding apertures in the jacquard and until the entire stocking has been completed at which time the engagement of the needle 130 in the stop aperture *f* will intercept any further feeding of the machine until the knitting machine has been set to knit a new stocking or set of stockings.

There is nothing in this arrangement which would act to prevent the operator stopping the machine by manually shifting the control rod as at present and any such intermediate stop *s* will have no effect on the automatic stopping of the machine at the prescribed point during the progress of the knitting operation. However, when a particular jacquard has been once set in control of the automatic stopping motion it is not possible for the operator to vary the number of courses to be knit between the successive automatic stoppings of the machine. As long as the jacquard is in control the requisite number of courses defined by the jacquard must be completed and in this way the number of courses knit in the several portions of the stocking or other article is beyond the control of the operator.

Having thus described my invention, I 65 claim:

1. In a knitting machine, the combination of a power shaft adapted to act in synchronism with the knitting operation of the machine and a member for stopping the machine, of a jacquard controlled mechanism for causing said member to function successively at the termination of a predetermined number of courses knit by the machine in accordance with the jacquard pattern for the time being in control of said mechanism, said mechanism comprising a step-by-step jacquard advancing means actuated from said shaft, a jacquard advanced by said means and provided with two parallel lines of pattern forming apertures, said jacquard advancing means comprising a control therefor including a pin coacting with the apertures in one of said lines selectively to cause a single step of advance of the jacquard either at the termination of a plurality of knitted courses or at the termination of a single knitted course, said jacquard controlled mechanism also comprising machine stopping means adapted to be cooperatively connected with said stopping member and including a pin coacting with the apertures in the other line for causing said machine stopping means to act on the stopping member and thus cause the machine to stop. 95

2. In a knitting machine, the combination of a machine stopping member, a power member, jacquard controlled means for connecting the power member to the stopping member to stop the machine, said jacquard controlled means including a floating pin, mechanism for feeding an apertured jacquard with a step-by-step movement past the pin and in position to permit the pin to fall into an aperture in the jacquard and thus connect the power member to the stopping member, a replaceable jacquard advanced by said mechanism and provided with a line of pawl controlling pattern apertures, said feeding mechanism including a feed sprocket provided with a feed ratchet, a step-by-step multiplier which permits a single step of movement of the feed sprocket ratchet after a predetermined number of steps of the multiplier, a pawl actuated by the power member for selectively advancing either the ratchet or the multiplier and means controlled by the line of pawl controlling apertures in the jacquard for selectively controlling the engagement of the pawl with the ratchet and multiplier. 110

3. In a knitting machine, the combination of a machine stopping member acting in synchronism with the knitting operation of the machine, a jacquard controlled mechanism for causing the stopping member to function, said mechanism including a jacquard advancing means operatively connected to be actuated from said power member, a jacquard ad-

vanced by said means and including three pattern forming means disposed transversely of the direction of advance of the jacquard, said advancing means including a control 5 governed by one of said three pattern forming means for regulating the rate of advance of said jacquard relative to the action of the knitting machine, means governed by another 10 of said three pattern forming means for causing said stopping member to function and means governed by the third of said three pattern forming means for disconnecting said jacquard advancing means from the power member.

15 4. In a knitting machine, the combination of a machine stopping member, a power member acting in synchonism with the knitting operation of the machine, a jacquard controlled mechanism for causing said stopping 20 member to function and including a jacquard feeding means actuated from said power member, a jacquard advanced by said feeding means, and provided with two parallel lines of pattern forming means, said feeding means 25 including a control therefor governed by one of said lines of pattern forming means for controlling the rate of advance of the jacquard relative to the knitting operation of the machine, and means governed by the other 30 line of pattern forming means for causing the stopping member to function.

5. In a knitting machine, the combination with a machine stopping member and a power shaft turning a unit number of degrees for

each course knit by the machine, of jacquard 35 controlled mechanism for stopping the machine successively at the termination of predetermined numbers of courses knit by the machine, said mechanism including a step-by-step jacquard advancing means actuated by 40 said power shaft, a jacquard advanced by said means and provided with a line of apertures comprising a plurality of sets of apertures, one of said sets comprising first and second apertures spaced apart a distance 45 equal to a plurality of steps of advance of the advancing means and each succeeding aperture beginning with the third being spaced from its preceding aperture a unit 50 distance of advance of the advancing means and said set of apertures including a single aperture laterally offset from the last aperture in the line, mechanism for controlling the rate of feed of the advancing means including a pin adapted when the pin is in engagement with the unperforated portion of the jacquard to cause a unit advance of said 55 advancing means following a predetermined number of course knit and when in one of said line of apertures to cause a unit advance 60 of said advancing means with each course knit and mechanism including a pin adapted when in the laterally offset aperture to cause the stopping member to function.

Signed at Milwaukee, in the county of 65 Milwaukee, and State of Wisconsin, this 30th day of August, A. D. 1926.

ROBERT BREYER.
